SUPPRESSOR

Edward W. Caulfield, St. Petersburg, Fla.

Application October 8, 1941, Serial No. 414,179

1 Claim. (Cl. 181—56)

The present invention relates to new and useful improvements in exhaust noise suppressors, particularly for airplane engines, although it will be understood, of course, that the device may be used in conjunction with any other type of internal combustion engine for which it may be found adapted and desirable.

The primary object of the invention is to provide, in a manner as hereinafter set forth, a suppressor of the character described which will substantially eliminate the noise of the exhaust while creating little or no back pressure on the engine.

Another very important object of the invention is to provide a suppressor of the aforementioned character embodying a novel construction and arrangement whereby the danger of fire will be reduced to a minimum.

Still another very important object of the invention is to provide an internal combustion engine exhaust noise suppressor from which no flame will be discharged, this being a highly desirable consideration, particularly on military airplanes when flying at night.

Other objects of the invention are to provide a suppressor of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in vertical longitudinal section through a suppressor constructed in accordance with the present invention.

Figure 2 is a cross-sectional view, taken substantially on the line 2—2 of Figure 1.

Figure 3 is a cross-sectional view, taken substantially on the line 3—3 of Figure 1.

Figure 4 is a detail view in rear elevation, looking at the front spreader from the line 4—4 in Figure 1.

Figure 5 is a view in side elevation of the device.

Figure 6 is a view in side elevation of the tube and rear spreader unit.

Figure 7 is a view in rear elevation of the unit shown in Figure 6.

Referring now to the drawing in detail, it will be seen that the embodiment of the invention

which has been illustrated comprises an elongated casing 1 of suitable metal or other material, which casing may be of any desired dimensions. The casing 1 includes detachably connected front and rear sections 2 and 3, respectively. Fixed in the forward end portion of the rear section 3 is a metallic ring 4. The front section 2 slips on the rear sections 3 and is firmly secured thereto by bolts 5 which are threaded into the ring 4.

The front section 2 includes a substantially tapered or conical portion 6 which terminates, at its forward end, in a neck 7 for connection with the exhaust pipe from the engine (not shown). Welded at 23 in the neck portion 7 and extending rearwardly therefrom in the casing section 2 is a plurality of brackets 8. Mounted on the rear end portions of the brackets 8 is a substantially conical spreader 9. The brackets 8 terminate in inwardly and forwardly bent rear end portions 10 to which the spreader 9 is secured.

The rear end portion 11 of the casing section 3 is formed to provide a centrally located, forwardly protruding bell or the like 12. Mounted in the bell 12 and projecting rearwardly therefrom is a discharge neck 13.

Mounted in the front casing section 2 in abutting engagement with the forward end of the section 3 and the ring 4 is a circular, apertured metallic plate 14. A bead or rib 15 is welded at 24 in the section 2 and retains the plate 14 in position against the forward end of the section 3 and the ring 4.

Fixed in the apertures in the plate 14 is a plurality of tapered, rearwardly converging tubes 16. Mounted on the rear end portions of the tapered tubes 16 is a comparatively small apertured metallic plate 17. In the embodiment shown, the plate 17 has projecting from its periphery a plurality of ears 18. Mounted on the ears 18 and extending rearwardly and inwardly therefrom is a plurality of rods 19. A substantially conical spreader 20 is mounted on the rods 19 adjacent the rear ends of the tubes 16.

It is thought that the manner in which the suppressor functions will be readily apparent from a consideration of the foregoing. Briefly, the exhaust gases from the engine enter the casing section 2, said gases striking the spreader 9 and expanding in the chamber 21. From the chamber 21 the exhaust gases pass through the tapered, rearwardly converging tubes 16 into the casing section 3. The exhaust gases emerge from the tubes 16, strike the spreader 20 and again ex-

pand, this expansion occurring in the chamber 22. As indicated by the arrows in Figure 1 of the drawings, the exhaust gases are directed forwardly by the bell 12 into the conical spreader 20 where they again reverse and discharge through the neck 13. As will be readily apparent, access to the interior of the device may be expeditiously had by disconnecting the casing sections 2 and 3.

It is believed that the many advantages of a suppressor constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A suppressor comprising an elongated cylind-

rical casing having an inlet in one end and an outlet in its other end, a substantially conical baffle mounted in the casing in spaced, concentric relation thereto and in longitudinal alignment with the inlet, a circular apertured plate mounted in the casing rearwardly of the baffle, a plurality of imperforate, rearwardly tapering and converging tubes mounted in the apertures in the plate, a plate mounted on the rear end portions of the tubes and spaced from the casing, integral ears radiating from the second-named plate, rearwardly projecting rods mounted on said ears, a substantially conical baffle mounted on said rods in spaced, opposed relation to the tubes and spaced from the casing, and a bell on the rear end of the casing for directing exhaust gases forwardly into the second-named baffle.

EDWARD W. CAULFIELD.
